[57] **CLAIM**

The ornamental design for a rebar support and nailing block holder, as shown and described.

DESCRIPTION

FIG. 1 is a perspective view of the rebar support and nailing block holder;

FIG. 2 is front elevational view thereof, and it is un-

derstood that a rear view would be identical to FIG. 2;

FIG. 3 is a side elevational view thereof, and it is un-
derstood that a view of the opposite side would be identical to FIG. 3;

FIG. 4 is a top plan view thereof; and

FIG. 5 is a bottom view.

Fig. 1.

Fig. 2.

Fig. 3.

Fig. 4.

Fig. 5.
